US00D604882S

(12) **United States Design Patent**
Mier-Langner et al.

(10) **Patent No.:** **US D604,882 S**
(45) **Date of Patent:** **** Nov. 24, 2009**

(54) **TRACK FIXTURE LUMINAIRE**

(75) Inventors: **Alejandro Mier-Langner**, Providence, RI (US); **James E. Kuchar**, Fall River, MA (US)

(73) Assignee: **Genlyte Thomas Group, LLC**, Burlington, MA (US)

(**) Term: **14 Years**

(21) Appl. No.: **29/317,778**

(22) Filed: **May 6, 2008**

(51) **LOC (9) Cl.** **26-05**

(52) **U.S. Cl.** **D26/63**

(58) **Field of Classification Search** D26/60, D26/61, 62, 63, 64, 65, 66, 72, 81, 88, 89, D26/90, 91, 154, 24, 44, 77, 119, 121, 152, D26/75, 85; 362/145, 147, 148, 150, 218, 362/220, 223, 648, 227, 238, 239, 249, 250, 362/372, 418, 430, 269, 270, 271, 272, 273, 362/274, 277, 278, 282, 283, 285, 287, 288, 362/290, 309, 427

(57) **CLAIM**

The ornamental design for a track fixture luminaire, as shown and described.

DESCRIPTION

FIG. 1 is a perspective view of the track fixture luminaire of the present invention;

FIG. 2 is a front view of the design of the present invention;

FIG. 3 is a rear view of the design of the present invention;

FIG. 4 is a left side view of the design of the present invention;

FIG. 5 is a right side view of the design of the present invention; and,

FIG. 6 is a bottom view of the design of the present invention.

The broken lines showing environmental structure are for illustrative purposes only and form no part of the claimed design.

1 Claim, 6 Drawing Sheets
